(57) **CLAIM**

I claim the ornamental design for a flooring transition, as shown and described.

DESCRIPTION

FIG. 1 is a perspective view of the flooring transition.
FIG. 2 is a right side elevation view of the flooring transition.
FIG. 3 is a left side elevation view thereof.
FIG. 4 is a top view of the transition.
FIG. 5 is a bottom view thereof.
FIG. 6 is a front elevation view thereof; and,
FIG. 7 is a rear elevation view of the transition.
The flooring transition has been broken in the center for ease of illustration.
The broken lines are for illustrative purposes only and form no part of the claimed design.
